UNITED STATES PATENT OFFICE.

JOHN WILLIAM HASBURG, OF CHICAGO, ILLINOIS.

DESIGN FOR A PAINT PRODUCT AND PALETTE.

45,257.

Specification for Design.

Patented Feb. 17, 1914.

Application filed August 7, 1911. Serial No. 642,898. Term of patent 14 years.

To all whom it may concern:

Be it known that I, JOHN W. HASBURG, a citizen of the United States, residing at Chicago, in the county of Cook and State of Illinois, have invented a new, original, and ornamental Design for a Paint Product and Palette, of which the following is a specification, reference being had to the accompanying drawing, forming a part thereof.

Figure 1 is a plan view and Fig. 2 is an elevation of my design which consists of a square glass plate, or palette, having deposited thereon, gold paint, in mastic form, and fashioned into an artistic and ornamental design, pleasing in appearance to the prospective purchaser.

The plate is made of glass, and the paint, which is intended for ceramic decoration is

of plastic consistency and is deposited upon the glass palette in the central zone thereof, and is fashioned so as to produce a series of concentric depressions and elevations pleasing to the eye and forming an ornamental product. The paint in every instance is of a dark chocolate brown color.

My design therefore consists of a glass palette with a deposit brown paint near the center thereof, said paint being fashioned into the form shown in the drawing.

I claim:

The ornamental design for a paint product and palette, as shown and described.

JOHN WILLIAM HASBURG.

Witnesses:

W. LINN ALLEN,

MARY F. ALLEN.
